UNITED STATES PATENT OFFICE.

ACHILLE BIENVENU, OF MONTREAL, QUEBEC, CANADA.

DESIGN FOR A CARTON.

Application filed February 26, 1923. Serial No. 5,257. Term of patent 14 years.

To all whom it may concern:

Be it known that I, ACHILLE BIENVENU, a subject of the King of Great Britain, and resident of 201 Bellechasse Street, in the city and District of Montreal, in the Province of Quebec, in the Dominion of Canada, have invented a new, original, and ornamental Design for Cartons, of which the following is a specification, reference being had to the accompanying drawing, forming part thereof.

Figure 1 is a front perspective view of the carton.

Figure 2 is an end perspective view of the carton.

I claim:—

The ornamental design for a carton, as shown.

ACHILLE BIENVENU.
